UNITED STATES PATENT OFFICE.

HARRY LERNER, OF BROOKLYN, AND ABE GINSBURG, OF NEW YORK, N. Y.

DESIGN FOR A CASSEROLE COVER.

Application filed July 21, 1926. Serial No. 18,428. Term of patent 3½ years.

To all whom it may concern:

Be it known that we, HARRY LERNER, a citizen of the United States, residing at 142 South Ninth Street, Brooklyn, county of Kings, city and State of New York, and ABE GINSBURG, a citizen of the United States, residing at 334 West 86th Street, city, county, and State of New York, whose post-office address is ½ H. Lerner Company, 302-304 Penn Street, Brooklyn, county of Kings, city and State of New York, have invented a new, original, and ornamental Design for a Casserole Cover, of which the following is a specification, reference being had to the accompanying drawing, forming part thereof.

Figure 1 is a perspective view of the casserole cover showing our new design; and Fig. 2 is a plan view.

We claim:

The ornamental design for a casserole cover, as shown.

HARRY LERNER.
ABE GINSBURG.
